WALTER MURRAY AND FREDERICK S. MURRAY, OF NEW YORK, N. Y.

SWITCH-PLUG.

1,186,121.

Specification of Letters Patent. Patented June 6, 1916.

Application filed August 5, 1910. Serial No. 575,644.

To all whom it may concern:

Be it known that we, WALTER MURRAY and FREDERICK S. MURRAY, both citizens of the United States, and residents, respectively, of the borough of Manhattan, city, county, and State of New York, have invented certain new and useful Improvements in Switch-Plugs, of which the following is a specification.

10 This invention relates to improvements in switch plugs designed to be readily inserted into and withdrawn from electrical sockets of plugging boxes or of other electrical contrivances.

15 The invention consists of the features hereinafter set forth and more particularly pointed out in the claims.

20 In the accompanying drawings forming part of this specification and in which like reference numerals designate corresponding parts in the several figures,—Figure 1 is a plan view of the switch plug. Fig. 2 is a section thereof on the line 2—2 of Fig. 1. Fig. 3 is a cross-section taken on the line 25 3—3 of Fig. 1. Fig. 4 is a cross-section taken on the line 4—4 of Fig. 2.

25 Referring now more particularly to the drawings, 1 is the body-portion of the switch plug which is preferably of rectangular shape in cross section, as shown. The body-portion is provided with two recesses 3 and 4 on opposite sides to receive the cable conductors 5 and 6 which branch from the cable 7. These recesses 3 and 4 are 30 preferably made of a depth sufficient to receive the conductor branches wholly beneath the outer surface of the body-portion.

35 8 and 9 are two spring contact plates 40 which have their forward ends bent over the forward end of the body-portion and there secured in place by end screws 10 and 11. These contact plates are located on the sides not occupied by the recesses 3 and 4. The end screws 10 and 11 enter metallic 45 plugs 12 and 13 which are buried in the body of the plug and extend rearward where they are exposed at the floors of the recesses 3 and 4 for connection with the 50 conductor branches 5 and 6. The conductor branches are secured to connectors which are connected with the plugs 12 and 13 by the screws 14 and 15. The spring contact

55 plates 8 and 9 tend to spring outward from the sides of the body-portion and have a limited movement toward and from the body-portion. This movement is limited by shoulders 17 and 18 carried at the rear end of the body-portion, these shoulders forming recesses which receive the free ends of 60 the contact plates. The free ends of the springs are thus protected from injury and are prevented from catching on extraneous bodies.

65 Formed integrally with the body-portion is an enlarged heel 19 which is provided with a groove 20 to receive the cable 7. Extending across the heel 19 and bridging the recess 20 is a heel block 21 which preferably is formed with a recess 22 to match 70 the recess 20, these two recesses forming a cylindrical opening for the cable. The heel 75 is provided with two extensible posts fixed therein and passing through apertures 23 and 24 of the heel block, the arrangement being such that the heel block may be clamped down in place by the extensible posts so as to firmly grip the cable and prevent any strain thereon being communicated to 80 the connectors at the ends of the conductor branches 5 and 6. This arrangement also serves to prevent the outer sheathing of the cable from slipping when the cable is under strain, and prevents this sheathing from 85 raveling.

85 In the preferred arrangement of the clamping posts each comprises a tube 25 which has an internal threaded portion 26 and a screw 27 which works in the threaded tube. When the posts are extended by 90 retracting the screws, the block 21 is released and may be slipped upward on the tubes as far as the heads of the screws or the washers 28 under the screw heads will permit. When the screws are turned in the opposite 95 direction the block 21 is forced downward firmly to place against the cable. The lower ends of the screws 27 are enlarged, as shown in Fig. 3, to prevent the screws from being completely withdrawn from the tubes. The 100 inner surface of the recesses 20 and 22 is provided with screw threads or is otherwise roughened so as to sink into and grip the outer surface of the cable.

105 29 is a projection extending from the forward end of the body-portion and between

the screws 10 and 11, its purpose being to prevent accidental electrical connection between these screws.

The body-portion, the heel and heel block are formed of insulating material.

What is claimed and what is desired to be secured by Letters Patent is:—

1. A switch plug comprising a body-portion provided with spring contact plates extending along two opposite sides thereof, said contact plates being bent over the forward end of the body-portion and there secured in place by end screws, said body-portion having shoulders at its rear end to engage the free ends of said spring contact plates and limit their movement from the sides of the body-portion.
2. A switch plug comprising a body-portion provided with contact plates extending along two opposite sides thereof, and having countersunk elongated recesses on the other two sides to receive the conductor branches, said contact plates being bent over the forward end of the body-portion and there secured in place by end screws, studs buried in the ends of the body-portion to receive said end screws and exposed in said

elongated recesses for connection with the conductor branches.

3. A switch plug comprising a body-portion provided with spring contact plates extending along two opposite sides thereof, and having countersunk elongated recesses on the other two sides to receive the conductor branches, said spring contact plates being bent over the forward end of the body-portion and there secured in place by end screws, studs buried in the ends of the body portion to receive said end screws and exposed in said elongated recesses for connection with the conductor branches, said body-portion having shoulders at its rear end to engage the free ends of said spring contact plates and limit their movement from the body-portion.

In testimony whereof, we have signed our names to this specification, in the presence of two subscribing witnesses.

WALTER MURRAY.
FREDERICK S. MURRAY.
